United States Patent Office

Des. 225,929
Patented Jan. 16, 1973

225,929

CHAIR

Don Ray Gill, Hammond, Ind., assignor to Mohasco
Industries, Inc., Amsterdam, N.Y.

Filed Apr. 22, 1971, Ser. No. 136,635

Term of patent 14 years

Int. Cl. D6—02

U.S. Cl. D6—68

The figure is a perspective view of a chair illustrating my new design.

The back of the chair is conventionally plain while the side not shown is substantially identical to the side shown.

I claim:

The ornamental design for a chair, as shown and described.
